UNITED STATES PATENT OFFICE.

AUBREY J. GRINDLE, OF CHICAGO, ILLINOIS, ASSIGNOR TO GRINDLE FUEL EQUIPMENT COMPANY, OF HARVEY, ILLINOIS, A CORPORATION OF ILLINOIS.

POWDERED-FUEL FURNACE FEEDER.

Application filed December 14, 1922. Serial No. 606,884.

To all whom it may concern:

Be it known that I, AUBREY J. GRINDLE, a citizen of the United States, residing at Chicago, in the county of Cook and State 5 of Illinois, have invented a certain new and useful Improvement in Powdered-Fuel Furnace Feeders, of which the following is a specification.

My present invention relates to improvements in apparatus of the type disclosed in my prior Patent 1,457,521, June 5, 1923, for feeding comminuted fuel, such as powdered coal, to furnaces, my particular purpose now being to provide a novel form of fuel feeding screw 10 and to arrange the same in a novel manner with respect to a fuel chamber and a fuel conduit, whereby undesirable blow-back of air from the conduit is prevented; to provide a rotatable disk adjustable with respect to the delivery end of the feed screw to break up the fuel during its delivery to the conduit and to provide cooperating teeth of a particularly beneficial character on the disk and an adjacent fixed portion of the mechanism, 15 whereby breaking up of the fuel is accomplished expeditiously and efficiently; to provide an air deflector in the nature of a plate adapted to cooperate with the disk and said feed screw to further eliminate undesirable blow-back of air from the conduit into the fuel chamber, and to provide means whereby the disk may be adjusted through said 20 plate to different operative positions with respect to the feed screw without disturbing its operative relation with respect to the plate.

With the foregoing and other purposes in view, my invention consists in the novel features of construction, combination and arrangement of parts as will be hereinafter more fully described, illustrated in the accompanying drawings and defined in the appended claims.

In the drawings wherein like characters 45 of reference denote corresponding parts in the different views,

Figure 1 is a longitudinal section through my fuel feeding apparatus, showing particularly the fuel chamber or hopper, the blower, and my improved fuel feed and air control devices;

Fig. 2, a longitudinal section through my improved feed screw;

Fig. 3, a section on the line 3-3 of Fig.

1, showing the air deflecting plate and its 55 relation with respect to the feed disk;

Fig. 4, a view similar to Fig. 3 showing the teeth carried by a fixed part of the apparatus for cooperation with the feed disk;

Fig. 5, a face view of the feed disk, showing 60 the form of the teeth thereon for cooperation with the teeth shown in Fig. 4; and

Fig. 6, a detail perspective showing the manner in which the air deflecting plate is 65 removably associated with the apparatus.

Referring now to the drawings in detail, 70 10 designates a fuel chamber or hopper that is connected by a relatively restricted cylindrical passage 11 with a fuel conduit 12, which latter, to one side of said passage, leads to a furnace or other burning apparatus, and to the other side of said passage has connected therewith a blower 13. The blower 13 is connected directly with or otherwise suitably driven by a motor 14 and the latter also is suitably connected with a screw 15 for feeding fuel from the hopper through 75 said restricted passage to the conduit. Thus, when the motor is in operation a current of air is forced through the conduit to admix 80 with the fuel and effect its delivery to the furnace, a suitable valve 16 being provided in the conduit, between the passage 11 and the blower, whereby the flow of air may be regulated in desired proportion to the feed 85 of the fuel.

The feed screw 15 consists of a core that, 90 preferably, is formed of two solid sections 17 and 18 non-rotatably secured together in end to end relation, one section, 17, being cylindrical and the other section, 18, being of tapering form and flaring gradually outward from the cylindrical section. Each section is provided with threads 19, all of 95 which are of uniform outside diameter throughout the length of the screw, and the threads of each section are continuous with respect to the threads of the other section, as shown. This feed screw is arranged with 100 its cylindrical core portion within the restricted cylindrical passage 11 and its tapered core portion within the hopper, and is adapted to be rotated to effect delivery of fuel from the hopper through said passage 11 to the conduit, to which end it is provided 105 with axial trunnions or shafts 20, 21 that extend from its ends and are journaled, respectively, in suitable bearings 22, 23, the

former of which is carried by a plate 24 that closes an opening 25 in a wall of the conduit through which the screw is insertable and removable, and the latter of which is formed 5 with the housing 26 which encloses a suitable variable speed gear mechanism. A belt 27 connects a pulley 28 on the motor 14 with a pulley 29 on a shaft 30 of the variable speed gearing, whereby the screw is driven 10 from the motor, and by reason of the variable speed gearing, the speed of rotation of the screw may be varied without disturbing the speed of the motor and the blower, all as set forth in my prior Patent 1,457,521 afore- 15 mentioned.

By providing a feed screw of the character shown and by arranging the same in the manner mentioned, I accomplish two important and beneficial purposes; to wit, I provide 20 for constant and uniform feed of the fuel into the conduit, and I avoid undesirable blow-back of air from the conduit into the fuel chamber. The first of these purposes is accomplished as a result of tapering the 25 core of the screw, which assures a progressively greater amount of fuel being moved forward as the delivery end of the screw is approached; thereby preventing packing of the fuel between the threads and arching of 30 the same over the screw, particularly when the fuel is damp. The second purpose is accomplished as a result of disposing the cylindrical portion of the screw within the cylindrical passage 11, the latter thereby 35 being maintained full of fuel throughout its length when the apparatus is in operation and a barrier thus being formed that prevents the air in the conduit from reaching the fuel chamber. Furthermore, by forming 40 the threads of the screw of uniform outside diameter throughout its length, the fuel is fed into the passage 11 at the same rate that it is discharged therefrom, so that the fuel barrier aforementioned is constantly 45 maintained, yet packing of fuel within said passage is prevented.

Mounted on the shaft 21 for rotation therewith is a disk 31 that is adapted to break up the fuel as it is delivered into the 50 conduit 12 by the feed screw. This disk is so disposed with respect to the wall of the conduit surrounding the passage 11 that a space is provided between the disk and said wall through which the fuel passes during 55 its delivery to the conduit, and as shown, the disk is longitudinally adjustable along the shaft 20, whereby the width of this space may be varied. Adjacent faces of the disk and said wall of the conduit are provided 60 with ribs 32 and 33, respectively, that are substantially radially disposed, although curved, and that in width taper outwardly, the result being that said teeth are relatively 65 closely disposed adjacent the axis of the screw and diverge relatively outward, where-

by the fuel, as it is delivered in compact form between them is first thoroughly broken up and subsequently delivered in powdered form into the conduit.

As is apparent, the air current produced 70 by the blower 14 travels transversely across the delivery end of the feed screw and the fuel falls by gravity into the conduit and is picked up and delivered by said air current to the furnace. Accordingly, it is desirable 75 to provide means to substantially separate the delivery end of the feed screw from the conduit, so that the air current will not interfere with the free feed of the fuel, and to this end I dispose within the conduit, 80 somewhat in advance of the delivery end of the screw, a plate 34 which is turned inwardly along its bottom edge in the direction of and below the screw and terminates in spaced relation to a relatively outwardly 85 extending lip 35 on the adjacent wall of the conduit, whereby a narrow opening is provided through which the fuel may fall into the conduit and whereby the latter otherwise 90 is separated from the screw. Said plate is 95 provided with an opening 36 within which the disk 31 operates and said disk is provided with a laterally extending peripheral flange 37, whereby it may be longitudinally 100 adjusted along the shaft 20 and through said opening within predetermined limits and at the same time maintain said opening substantially closed. The plate 34 rests on and 105 between lugs 38 on opposite side walls of the conduit as shown in detail in Fig. 6 of 110 the drawings and thereby is removable after the shaft 20 and disk 31 have been withdrawn from within its opening 36. By the use of this plate the air current, as it travels 115 past the narrow opening between the bottom of the plate and the lip 35, creates in effect a partial vacuum between the plate and the adjacent wall of the conduit, which tends to draw the fuel away from the delivery end of the screw and thereby assists in obtaining 120 continuous, uniform feed of fuel into the conduit, and further eliminates the possibility of undesirable blow-back of air into the fuel chamber.

I claim:

1. In mechanism of the class described, a fuel chamber, a conduit, a feed screw for delivering fuel from said chamber to said conduit, means for forcing a current of air through said conduit to effect delivery of the fuel supplied thereto by said feed screw, a rotatable disk disposed within said conduit in advance of the delivery end of said feed screw to break up the fuel during its delivery to the conduit, and a plate disposed within the conduit in advance of the delivery end of said feed screw to avoid blow-back of the air from said conduit into the fuel chamber, said plate having an opening 130 within which the disk operates.

2. In mechanism of the class described, a fuel chamber, a conduit, a feed screw for delivering fuel from said chamber to said conduit, means for forcing a current of air through said conduit to effect delivery of the fuel supplied thereto by said feed screw, a rotatable disk disposed within said conduit in advance of the delivery end of said feed screw to break up the fuel during its delivery to the conduit, said disk being adjustable toward and away from the delivery end of said feed screw, a plate disposed within the conduit in advance of the delivery end of said feed screw to avoid blow-back of the air from said conduit into the fuel chamber, said plate having an opening within which the disk operates, and the disk being provided with a laterally extending peripheral flange whereby the opening in said plate is maintained substantially closed by said disk in different adjusted positions of the latter toward and away from said feed screw.
3. In mechanism of the class described, a fuel chamber, a conduit, a feed screw for delivering fuel from said chamber to said conduit, means for forcing a current of air through said conduit to effect delivery of the fuel supplied thereto by said feed screw, a rotatable disk disposed within said conduit in advance of the delivery end of said feed screw to break up the fuel during its delivery to the conduit, said disk being adjustable toward and away from the delivery end of said feed screw, a plate disposed within the conduit in advance of the delivery end of said feed screw to avoid blow-back of air from said conduit into the feed chamber, said plate having an opening within which the disk operates, and means whereby the opening in said plate is maintained substantially closed by said disk in different adjusted positions of the latter toward and away from said feed screw.
4. In mechanism of the class described, a fuel chamber, a conduit, a feed screw for delivering fuel from said chamber to said conduit, means for forcing a current of air through said conduit to effect delivery of the fuel supplied thereto by said feed screw, a disk disposed within said conduit in advance of the delivery end of said feed screw to break up the fuel during its delivery to the conduit, said disk being adjustable toward and away from the delivery end of said screw, and means surrounding said disk and extending to portions of the walls of said conduit adjacent thereto whereby blow-
- back of air from said conduit into the fuel chamber is avoided.
5. In mechanism of the class described, a fuel chamber, a vertically extending conduit, a horizontally disposed feed screw for delivering fuel from said chamber to said conduit, means for forcing a current of air upwardly through said conduit and across the delivery end of said feed screw to effect delivery of fuel supplied to said conduit by said feed screw, and means to cause all fuel to be delivered in a downward direction from said feed screw to said conduit.
6. In mechanism of the class described, a fuel chamber, a vertically extending conduit, a horizontally disposed feed screw for delivering fuel from said chamber to said conduit, means for forcing a current of air upwardly through said conduit and across the delivery end of said feed screw to effect delivery of fuel supplied to said conduit by said feed screw, and means substantially separating the delivery end of said feed screw from said conduit and restricting communication between the fuel chamber and the conduit to a narrow opening disposed below the delivery end of the feed screw.
7. In mechanism of the class described, a fuel chamber, a vertically extending conduit, a horizontally disposed feed screw for delivering fuel from said chamber to said conduit, means for forcing a current of air upwardly through said conduit and across the delivery end of said feed screw to effect delivery of fuel supplied to said conduit by said feed screw, a plate disposed in advance of the delivery end of said feed screw and at substantially right angles to the axis thereof, said plate extending at its top and sides into contact with adjacent portions of the walls of said conduit and at its bottom edge being turned inward towards said feed screw, and an outwardly extending lip on the wall of said conduit below said feed screw cooperating with the lower edge of said plate to restrict communication between said fuel chamber and said conduit to a narrow opening disposed below the delivery end of the feed screw, thereby to cause all fuel to be delivered in a downward direction from said feed screw to said conduit and avoid blow-back of air from said conduit into the fuel chamber.

In witness whereof, I have hereunto subscribed my name.

AUBREY J. GRINDLE.
